UNITED STATES PATENT OFFICE.

ALBERT G. HADCOCK AND GEORGE FORSTER, OF NEWCASTLE-UPON-TYNE, ENGLAND,
ASSIGNORS TO SIR W. G. ARMSTRONG, WHITWORTH AND COMPANY, LIMITED, OF
NEWCASTLE-UPON-TYNE, ENGLAND.

AUTOMATIC GUN.

1,360,523.

Specification of Letters Patent. Patented Nov. 30, 1920.

Application filed June 22, 1920. Serial No. 390,958.

To all whom it may concern:

Be it known that we, ALBERT GEORGE HADCOCK, K. B. E., F. R. S., and GEORGE FORSTER, subjects of the King of Great Britain, 5 residing at Elswick Works, Newcastle-upon-Tyne, England, have invented new and useful Improvements in Automatic Guns, of which the following is a specification.

10 Our invention relates to the type of automatic gun in which a number of cartridges carried by a rotatable holder situated within a drum are conveyed one by one by a carrier into line with the axis of the gun 15 and automatically pushed into the chamber of the gun by a rammer.

Our invention also relates to rammer mechanism used in conjunction with a pivoted cartridge carrier of the type in which 20 the recoil of the gun pushes back the rammer which is retained in its cocked position by a spring catch and is tripped at the proper time as the gun runs out by an incline or lug on the gun.

25 The main object of our invention is to provide improved mechanism which will function properly at all angles of elevation or depression despite considerable variations in the length of the recoil.

30 According to our invention the cartridges are taken one by one from a rotatable cartridge holder and conveyed to the chamber of the gun by a carrier pivoted to the mounting, the arrangement being such that 35 the closing of the breech turns the carrier into position to receive a fresh cartridge and causes a partial rotation of the holder.

In order to transfer the cartridge from the carrier into the breech a spring actuated 40 rammer is mounted on the carrier, the rammer spring being compressed by the rearward movement of the gun; when the gun has recoiled a certain distance the rammer is held in the cocked position and moved 45 clear of the gun behind a cartridge in the carrier and is automatically released when the carrier has brought the cartridge in line with the gun.

In one way of carrying out our invention 50 we secure to an arm on the mounting a cylindrical drum within which the cartridges are made to revolve by means of a feeding wheel at one end thereof. This wheel is provided with projecting fingers in

number equal to the number of cartridges 55 the drum can hold, and the cartridges remaining in the drum are revolved around the axis of the drum each time the breech is closed.

For conveying the cartridges in succession from the drum to a position in line with the bore, we provide a hinged cartridge carrier. When the gun is in the firing position the cartridge carrier is clear 60 of the recoil of the gun and rests either 65 against the side of the breech block or against a projection formed on the latter. When the gun is in recoil the carrier bears against the side of the gun until the gun is nearly run out again. The breech having 70 been opened either during the recoil or the run out and the gun having run clear of the carrier as it nears home on the run out movement, the carrier is swung into the loading position by a spring. In the carrier 75 we place a rammer spring either immediately behind the leading cartridge or by its side. When the spring is placed alongside it is contained in a hollow plunger, and to one side of this plunger is pivoted 80 a rammer lever which is automatically held in the cocked position toward the end of the recoil and is automatically tripped to ram the cartridge into the chamber at the end of the run out. As the gun is recoiling 85 the rammer lever is pushed back by the gun until it reaches the rear of the cartridge in the carrier, when it is simultaneously moved behind the cartridge and freed from contact with the gun. The rammer is held 90 in the cocked position by a lever pivoted on the carrier and this lever is so arranged that as soon as the cartridge is brought into loading position the lever is released by coming into contact with a projection on the 95 stationary arm to which the carrier is attached. The cartridge is then thrown forward into the chamber by the action of the rammer spring, the flange of the cartridge strikes the extractors which are holding 100 the breech block open and so frees the breech block which closes by the action of a spring. The block in closing pushes the carrier back into position for receiving another cartridge. As the carrier returns to the 105 feed drum a flexible lever pivoted on the carrier catches a finger on the feeding wheel and revolves the cartridge holder inside the

- drum, the required amount to bring the next cartridge into the carrier. As the cartridge is pushed into the carrier it returns the rammer lever to its original position.
- 5 The carrier is provided with a circular projection for preventing the holder inside the drum from turning when the carrier is either in or moving to and from the loading position.
- 10 In the accompanying drawings which illustrate the invention, complementary Figures 1 and 1^a are sectional elevations and complementary Figs. 2 and 2^a sectional plans of Fig. 1. Fig. 3 is an end elevation, the 15 breech mechanism and cartridge carrier being in the loading position. Fig. 4 is a plan view with the breech mechanism and cartridge carrier in the loading position, and Fig. 5 is an end elevation of Fig. 4. Figs. 20 3 and 5 are drawn to a larger scale than Figs. 1, 2 and 4.
- 1 is the gun which slides in the cradle 2 during recoil. The cradle 2 is pivoted on trunnions 3 to the mounting. The gun 1 is run out after recoil by a spring contained 25 in the cylinder 4. 5 is a sliding breech block which (in the example shown) opens during the run out of the gun. 6 is a cylindrical drum for holding five cartridges, one 30 end of the drum being mounted on a support 7 on the cradle 2, and the other end on an arm 8 carried by a bar 9 fixed to the cradle 2. The drum 6 is held in position by pins 10 so that it can be readily detached or 35 mounted. In the drum 6 is an opening sufficiently large to admit a cartridge, and covered by a lid 11. Within the drum 6 is a cartridge holder 12 having teeth or arms to carry in the example shown five cartridges.
- 40 The cartridge holder 12 is provided with a feed wheel 13 having fingers equal in number to the number of cartridges in the drum 6, and is rotated a sufficient amount to bring a cartridge into position to charge a carrier 14 each time the breech closes.
- 45 The carrier 14 which conveys the cartridges in succession from the drum 6 to a position in line with the bore, is hinged on the bar 9 and so situated that it clears the gun 1 during recoil as shown in Fig. 3. The carrier 14 is held clear of the gun 1 by a projection 15 on the breech block 5 against the action of the spring 16. When the gun is in recoil the carrier 14 bears against the 50 side of the gun 1 until the gun is nearly run out again. During the run out the breech is opened in any usual manner and when the gun nears home on the run out movement it clears the carrier 14 which is swung into the loading position by the spring 16. On the carrier 14 is a cylinder 17 containing a hollow plunger 18 to one side of which is pivoted a rammer lever 19 having an extension 20 situated immediately behind the 55 breech block 5 so that when the gun recoils the plunger 18 is moved rearwardly by the extension 20 to compress a spring 21 until the plunger 18 is cocked by a lever 22 pivoted at 23 to the carrier 14 and actuated by the spring 24. As soon as the rammer lever 19 reaches the rear end of the cartridge, it is turned anti-clockwise to the position shown in Fig. 5 by a projection 25 on the lever 19 which comes against a sloping face 27 formed on the carrier 14. This movement 60 also causes the extension 20 to be moved away from the breech block, so that the gun may recoil any farther distance without affecting the rammer 19.
- When the carrier 14 moves into the loading position the lever 22 is moved to release the plunger 18 by a projection 28 on the bar 9, which comes into contact with the lower end of the lever 22. The cartridge is then thrown forward into the chamber of 65 the gun by the action of the spring 21.
- As the cartridge goes home in the chamber, the breech block 5 is released and closes, the projection 15 on the breech 5 pushing the carrier 14 back into position for receiving another cartridge.
- 70 As the carrier 14 moves toward the drum 6 a pawl 29 pivoted on the carrier 14 engages with a finger on the wheel 13 and revolves the holder 12 inside the drum 6 the 75 required amount to bring the next cartridge into the carrier 14. The cartridge in its movement into the carrier 14 bears against the rammer 19 and returns the extension 20 into position behind the breech block 5 so as 80 to be engaged by the projection 15 thereon, when the gun recoils.
- 85 The carrier 14 is provided with a circular projection 30 for preventing the holder 12 from turning when the carrier 14 is in the 90 loading position and in part of the movement to and from the loading position.
- 95 What we claim is:—
1. The combination of a gun mounting, a cartridge carrier pivoted to the mounting, a rammer and a rammer spring mounted on the carrier and adapted to be compressed by the rearward movement of the gun, means whereby when the gun has traveled part of its recoil the rammer is held in the 100 cocked position and moved to allow of further recoil clear of the gun behind a cartridge in the carrier and means whereby the rammer is automatically released when the carrier has brought a cartridge in line 105 with the gun.
  2. The combination of a gun mounting, a cartridge carrier pivoted to the mounting, a plunger mounted on the carrier, a spring for actuating said plunger, a rammer lever 110 carried by said plunger and adapted to be moved rearwardly by the recoil of the gun, a cam face on said carrier adapted to move the rammer clear of the gun and behind a cartridge in the carrier when the gun has trav- 115

eled part of its recoil, means adapted to cock the rammer and means whereby the rammer is automatically released when the carrier has brought a cartridge in line with the gun.

3. The combination of a gun mounting, a cartridge carrier pivoted to the mounting, a plunger mounted on the carrier, a spring for actuating said plunger, a rammer lever carried by said plunger and adapted to be moved rearwardly by the recoil of the gun, means adapted to move the rammer clear of the gun and behind a cartridge in the carrier when the gun has traveled part of its recoil, a lever pivoted to the mounting and adapted to hold the plunger in the cocked position, and a fixed projection adapted to tilt the lever and release said rammer when the carrier has brought a cartridge in line with the gun.

4. The combination of a gun mounting, a cartridge carrier pivoted to the mounting, a plunger mounted on the carrier, a spring for actuating said plunger, a rammer lever carried by said plunger and adapted to be moved rearwardly by the recoil of the gun, a cam face on said carrier adapted to move the rammer clear of the gun and behind a cartridge in the carrier when the gun has traveled part of its recoil, a lever pivoted to the mounting and adapted to hold the plunger in the cocked position, and a fixed projection adapted to tilt the lever and release said rammer when the carrier has brought a cartridge in line with the gun.

5. The combination of a gun mounting, a rotatable cartridge holder carried by the mounting, a cartridge carrier pivoted to the mounting and adapted to convey cartridges one by one from the holder to a position adjacent the chamber of the gun, and means whereby the closing of the breech turns the carrier into position to receive a fresh cartridge and causes a partial rotation of the holder.

6. The combination of a gun mounting, a cartridge carrier pivoted to the mounting, a rammer and a rammer spring mounted on the carrier and adapted to be compressed by the rearward movement of the gun, means whereby when the gun has traveled a part of its recoil the rammer is held in the cocked position and moved clear of the gun behind a cartridge in the carrier, means whereby the rammer is automatically released when the carrier has brought a cartridge in line with the gun, a rotatable cartridge holder carried by the mounting, a cartridge carrier pivoted to the mounting and adapted to convey cartridges one by one from the holder to a position adjacent the chamber of the gun, and means whereby the closing of the breech turns the carrier into position to receive a fresh cartridge and causes a partial rotation of the holder.

7. The combination of a gun mounting, a rotatable cartridge holder carried by the mounting, a cartridge carrier pivoted to the mounting and adapted to convey cartridges one by one from the holder to a position adjacent the chamber of the gun, means whereby the closing of the breech turns the carrier into position to receive a fresh cartridge and causes a partial rotation of the holder, and a projection on the carrier adapted to prevent the cartridge holder from rotating when the carrier is in the loading position and during part of its movement to and from the loading position.

8. The combination of a gun mounting, a cartridge carrier pivoted to the mounting, a rammer and a rammer spring mounted on the carrier and adapted to be compressed by the rearward movement of the gun, means whereby when the gun has traveled part of its recoil the rammer is held in the cocked position and moved clear of the gun behind a cartridge in the carrier, means whereby the rammer is automatically released when the carrier has brought a cartridge in line with the gun, a rotatable cartridge holder carried by the mounting, a cartridge carrier pivoted to the mounting and adapted to convey cartridges one by one from the holder to a position adjacent the chamber of the gun, means whereby the closing of the breech turns the carrier into position to receive a fresh cartridge and causes a partial rotation of the holder, and a projection on the carrier adapted to prevent the cartridge holder from rotating when the carrier is in the loading position and during part of its movement to and from the loading position.

9. The combination of a gun mounting, a rotatable cartridge holder carried by the mounting, a cartridge carrier pivoted to the mounting and adapted to convey cartridges one by one from the holder to a position adjacent the chamber of the gun, a pawl on the cartridge carrier adapted to engage with fingers on the holder, means whereby the closing of the breech turns the carrier into position to receive a fresh cartridge and causes a partial rotation of the holder, and a projection on the carrier adapted to prevent the holder from turning when the carrier is in the loading position and in part of the movement to and from the loading position.

10. The combination of a gun mounting, a rotatable cartridge holder carried by the mounting, a cartridge carrier pivoted to the mounting and adapted to convey cartridges one by one from the holder to a position adjacent the chamber of the gun, a pawl on the cartridge carrier adapted to engage with fingers on the holder, means whereby the closing of the breech turns the carrier into position to receive a fresh cartridge and causes a partial rotation of the holder, a spring actuated plunger, a rammer on said plunger, a

catch for retaining the plunger in its cocked position, and means for releasing the plunger.

11. The combination of a gun mounting, a rotatable cartridge holder carried by the mounting, a cartridge carrier pivoted to the mounting and adapted to convey cartridges one by one from the holder to a position adjacent the chamber of the gun, a pawl on the cartridge carrier adapted to engage with fingers on the holder, means whereby the closing of the breech turns the carrier into position to receive a fresh cartridge and causes a partial rotation of the holder, a projection on the carrier adapted to prevent the holder from turning when the carrier is in the load-

ing position and in part of the movement to and from the loading position, a cartridge carrier pivoted to the mounting, a rammer and a rammer spring mounted on the carrier 20 and adapted to be compressed by the rearward movement of the gun, means whereby when the gun has traveled a part of its recoil the rammer is held in the cocked position and moved clear of the gun behind a 25 cartridge in the carrier and means whereby the rammer is automatically released when the carrier has brought a cartridge in line with the gun.

A. G. HADCOCK.
GEORGE FORSTER.
